(57) **CLAIM**

The ornamental design for a shower rail slider, as shown and described.

DESCRIPTION

FIG. 1 is a perspective view of the shower rail slider in accordance with our new design;

FIG. 2 is another perspective view thereof, shown at a different angle than FIG. 1;

FIG. 3 is a rear view thereof;

FIG. 4 is a front view thereof;

FIG. 5 is a right side view thereof;

FIG. 6 is a left side view thereof;

FIG. 7 is a top plan view thereof; and,

FIG. 8 is a bottom view thereof.

The broken lines and unshaded areas of the shower rail slider form no part of the claimed design.

1 Claim, 6 Drawing Sheets
